(57) **CLAIM**

We claim the ornamental design for a motorcycle muffler, as shown and described.

DESCRIPTION

FIG. 1 is a perspective view of the motorcycle muffler, shown in position of use from the right side of a motorcycle.

FIG. 2 is an enlarged right side view of the motorcycle muffler.

FIG. 3 is a rear perspective view of the motorcycle muffler shown in FIG. 2; and,

FIG. 4 is a top view of the motorcycle muffler shown in FIG. 2.

The broken line showing of the environment is for illustrative purposes only and forms no part of the claimed design.
